UNITED STATES PATENT OFFICE.

ARTHUR I. HARVEY, OF PROVIDENCE, AND WILLIAM MARCROFT, OF CRANSTON, RHODE ISLAND, ASSIGNEES TO UNIVERSAL WINDING COMPANY, OF PORTLAND, MAINE, A CORPORATION OF MAINE.

WINDING-MACHINE.

1,087,368.

Specification of Letters Patent.

Patented Feb. 17, 1914.

Application filed July 31, 1912. Serial No. 712,490.

To all whom it may concern:

Be it known that we, ARTHUR I. HARVEY and WILLIAM MARCROFT, citizens of the United States, residing at Providence and 5 Cranston, respectively, in the county of Providence and State of Rhode Island, have invented certain new and useful Improvements in Winding-Machines, of which the following is a specification.

10 Our invention relates to winding machines for winding yarn and thread into cops or bobbins for use in loom shuttles and consists particularly of improvements in the "bunch-building" mechanism therefor.

15 The object of our invention is to simplify and improve the structural details of the mechanism shown and described in our pending application for patent, Serial No. 707,824, filed July 5, 1912, and to render the 20 device adjustable to regulate the length of yarn wound into the "bunch".

In the application referred to we have described a device adapted to operate in connection with a usual form of winding machine to automatically control the traverse of the thread-guide at the commencement of each bobbin so that several layers of yarn are wound with a relatively short traverse. By this means a short section of yarn is wound 30 on the naked bobbin or tube at the beginning of the winding to form what is technically termed a "bunch". The "bunch" coöperates with the "feeler-mechanism" of the loom to actuate the filling-replenishing device when the yarn in the bobbin becomes 35 nearly exhausted.

The invention is fully described in the following specification, illustrated by the accompanying drawings, in which:-

40 Figure 1 is a longitudinal elevation of a winding machine, showing our new device applied thereto, the main frame of the machine being illustrated in section to disclose the mechanism contained therein; Fig. 2, a 45 plan view of the same; Figs. 3 and 4, enlarged detail views of the stopping mechanism of the machine; Figs. 5, 6, and 7, detail views of parts of the bunch-building device; Figs. 8, 9, 10 and 11, enlarged views of 50 the assembled bunch-building mechanism with the parts shown in the different positions which they assume during successive stages of their operation.

Our invention is shown as applied to a machine of the same general type as that described in U. S. Patents Nos. 940,489 and 946,831, granted Nov. 16, 1909, and Jan. 18, 1910, respectively, to S. W. Wardwell.

The basic machine consists essentially of a rotating winding-spindle B and a reciprocating traverse-bar C, the latter arranged opposite the spindle, and adapted to carry the thread-guide G, which, besides its movement with the bar, is fed progressively outward thereon to build the cop in superimposed conical layers. The winding-spindle B is mounted in a bearing a in the main frame A of the machine and is rotated from the main driving-shaft E by means of skew-gears e, e'. The traverse-bar C slides in a 70 quill-shaped bearing a', which has an extension a² extending through a bore in the side of the frame A, and is reciprocated from a rocker-arm F mounted on the continuously-oscillated shaft D. Our new traverse-controlling device operates directly in connection with the arm F and is arranged to automatically adjust the point of connection of the traverse-bar C with the arm to vary the operative length of the latter and regulate the length of traverse of the thread-guide as more fully explained hereinafter.

The traverse-bar C is preferably constructed in two parts C' and C², the main portion C' sliding in the bearing a', as before explained, and the extension C² connected thereto at its outer end by a pin-and-slot coupling c. The outer end of the extension C² is mounted in a bushing c' which is swiveled in an outboard bearing j supported on a bracket J extending from the frame A. The coupling c allows the inner end of the extension C² to swing inward from the plane of the axis of the main portion C' of the bar, as shown in Fig. 2, while 95 the outer end of the bar swings in the swiveled bushing c'. This arrangement is the same as that described in U. S. Patent 940,489, above referred to, and provides that the contact means carried on the traverse-bar, and arranged to feed the thread-guide along the winding-spindle, shall contact with the first layers of yarn wound on the bobbin x before the base of the cop is built up to its maximum diameter. The progression or contact-mechanism is arranged as

now briefly described, a more comprehensive description being given in the patent just referred to.

The thread-guide G is preferably supported on a thread-guide holder or arm g, of bifurcated form, having two legs g', g' terminating in bearings g², g² surrounding the bar C². Between the bearings g², g² is an internally threaded sleeve 10 or nut h which carries a relatively thin disk H called the contact-wheel. The bar C² is formed with screw-threads c² extending approximately half way around its circumference and a spring h' is secured to the guide-holder g with its end bearing on a flange h² of the nut h. The spring h' acts to normally press the nut h into position to engage its threads with the threads c² on the bar C², but the bore of the nut is of sufficient 20 diameter to allow its threads to pass over those on the bar when the nut is pressed in the opposite direction against the force of the spring. It will be seen that while the machine is operating the nut h is engaged 25 with the threads on the bar C² so that the turning of the wheel H will feed the thread-guide along the winding-spindle, but by releasing the nut from engagement with the threads on the bar the guide can be slid back 30 to adjust it in position to begin the winding of a new bobbin.

Mounted on the end of the bar C' is a "former" K, so termed because it acts to direct the movement of the contact-wheel 35 H away from the winding-spindle during the building of the base or heel of the bobbin and therefore determines the form of the latter. The former K has an arm k arranged with its edge k' at an angle to the 40 axis of the winding-spindle, and by adjusting the arm at different angles the taper of the base of the bobbin can be regulated. Adapted to bear on the edge k' of the arm k is a follower-arm g³ extending rearwardly 45 from the thread-guide holder g. Sliding in a bore at the inner end of the bar C² is a spring-pressed plunger c³, adapted to bear against the inclined face c⁴ of the coupling-plate c and tending to normally hold the 50 bar C² in position to align its axis with that of the bar C'. The swinging movement of the bar C² is limited by its pin c⁵ sliding in the slot c⁶ of the plate c and when the follower g³ bears on the rearward end of 55 the former-arm k the end of the bar is held with the pin at the inner end of the slot as shown in Fig. 2. This provides that the contact-wheel H will be maintained in close proximity to the surface of the bobbin or 60 cop-tube at the beginning of the winding so that its periphery will contact with the first layers of yarn wound on the latter at the rearward end of each stroke of the thread-guide. The contact of the wheel with the 65 surface of the yarn, during the rotation of

the winding-spindle, acts to turn the wheel to feed the thread-guide outward along the spindle in the manner now well known to those versed in the art. As the thread-guide feeds outward along the traverse-bar C² the 70 follower-arm g³ slides along the incline of the arm k and allows the contact-wheel to recede from the axis of the winding-spindle in accordance with the growth in diameter of the winding. As the follower g³ reaches 75 the end of the arm k the base of the bobbin or cop attains its maximum diameter and the bar C² assumes a position in alinement with the bar C'. Henceforth the two sections C' and C² of the traverse-bar C are reciprocated 80 in the same plane, as one continuous bar, and the contact-wheel H engages the bobbin at the rearward end of each reciprocation at a point on the base of its forward conical end. In this way the bobbin grows by longitudinal 85 extension, the conical layers forming a substantially cylindrical body terminating in the tapered delivery end or nose.

The stopping-mechanism of the machine for arresting the rotation of the winding-spindle and the reciprocation of the thread-guide consists essentially of a rockable bridge-member L which is pivoted on suitable bearings in the frame A and extends across and above the shafts E and D. The 95 inner end of the member L is mounted on a rod l secured in the inner side of the frame A and the outer end is formed with a socket l' which receives the end of an extension L' secured in place by the screw l². The extension L' reaches through a bearing in the outer side of the frame A, and secured in a bore at its end is a rod M held by the set-screw m. The opposite end of the rod M passes through a bearing m' in the bracket 105 J and is bent down to form a handle M'.

The skew-gear e' which is driven from the gear e is mounted free to turn on the winding-spindle B and is connected rotatively therewith by means of a clutch-member N, see Figs. 1 and 2. The clutch-member N is keyed rotatively with the spindle, but is free to slide thereon to carry its tapered face n into and out of engagement with the corresponding face e² of the gear 110 e'. A coiled spring n' bearing against a collar n² tends to normally maintain the clutch-member N in engagement with the gear e' so that the winding-spindle is driven therefrom; and the clutch-member is released from the gear e' to arrest the rotation of the spindle by means of a lever l³. The lever l³ is preferably formed as a part of the bridge-member L and extends upwardly therefrom with its end adapted to 115 engage the beveled face of an annular flange n³ formed on the clutch-member N.

Referring to Figs. 2 and 3, the rocker-arm F which reciprocates the traverse-bar C is formed with a double hub f mounted 120

free on the shaft D and connected therewith by a clutch-block O secured on the shaft by a bolt o. Preferably, the hub f is provided with a key or spline f' adapted to 5 engage a corresponding slot o' in the face of the block O and a coiled spring o² bearing against a collar o³ tends to normally hold the hub f in engagement with the clutch-block. The hub f is disengaged from 10 the block O by means of the bridge-member L which is formed with an overhanging portion l⁴ having a face l⁵ adapted to engage with a tapered projection f² on the end of the hub f to slide the hub against 15 the action of the spring o², see Fig. 3. A double-ended spring l⁶, see Figs. 2 and 4, is secured to the top of the member L with its free ends l⁷, l⁸ reaching down adjacent the sides of the projection f² on the hub f of 20 the arm F. The ends of the spring l⁶ act to prevent excessive rocking movement of the arm F after its disengagement from the clutch-block O and serve to hold the arm in such relation to the clutch-block as to 25 insure the spline f' being engaged with the slot o' upon the release of the hub f from the member L.

Referring now to Figs. 8, 9, 10 and 11, the arm F is formed with a curved slot f³ 30 extending from its upper end to a point adjacent its hub f. Connected to the main portion C' of the traverse-bar C by a pin c⁷ is a link P carrying a stud p at its opposite end adapted to engage the slot f³. By sliding the stud p down in the slot f³ the operative effect of the arm F may be varied to shorten the extent of traverse imparted to the traverse-bar C and through the latter to the thread-guide G. At the commencement 35 of the winding of a bobbin the stud p is held at the lower end of the slot f³ and will therefore move through an arc of relatively short radius when the arm F is oscillated, so that the thread-guide is reciprocated with a relatively short traverse to build the bunch on the bobbin. When the bunch has been built up to the required 40 diameter, or, more properly speaking, when a sufficient length of yarn has been wound into the bunch, the stud p is shifted to the upper end of the slot f³ and the traverse-bar C will then be reciprocated with the maximum extent of traverse to wind the 45 full layers which form the main portion of the bobbin.

In our previously filed application, before referred to, the arm F is illustrated as formed in one piece with its hub f. In the present embodiment of the invention we 50 have preferred to construct the arm F separate from its hub so that it may be detached therefrom for the purpose now explained: It will be seen by reference to the drawings that all of the parts of the traverse-controlling or bunch-building device are carried

on the arm F and therefore the whole mechanism can be removed from the machine by simply taking the arm off of its hub. In the previously described arrangement it is necessary to withdraw the rock-shaft D from the hub f in order to remove the arm F from the machine and this requires taking down a considerable part of the mechanism and entails a considerable amount of labor. This is particularly true when the machines are arranged in series, as is usual, with a large number of units or heads having one common rocker-shaft to operate all of their traverse-mechanisms. Sometimes it becomes necessary to adjust or repair a part of the bunch-building mechanism and the most convenient method of doing this is to remove the complete device. This is easily accomplished with the present arrangement of the detachable arm F and, furthermore, another advantage is gained thereby because the mechanism of the machine can be made interchangeable for performing different varieties of winding. For the ordinary method of winding bobbins without first building up the bunch a simple rocker-arm, similar to that shown in the previous patents to S. W. Wardwell, Nos. 940,489 and 946,831, of Nov. 16, 1909, and Jan. 18, 1910, might be employed and should it be required to adapt the machine for bunch-winding the plain arm can be removed and the present device substituted therefor. Any suitable method of attaching the arm F might be employed, but we have preferred to illustrate it as formed with an arcuate flange f⁷ fitted to the periphery of the hub f and secured in place by the screws f⁸, f⁹.

The bunch-building mechanism is arranged as follows: Pivoted on a screw r at the top of the arm F is a sector R which extends downward to a point adjacent the hub f. The sector R is preferably constructed of sheet-metal and formed with an arcuate slot r' arranged concentric with the axis of its pivot r. Its lower edge is formed with a series of ratchet teeth r². The slot r' is positioned to register with the bottom of the slot f³ of the arm F and is adapted to engage with the stud p, secured in the end of the link P, when the stud is in its lowermost position. By moving the sector into the position shown in Fig. 10 the stud p is held at the bottom of the slot f³ to adapt the arm F to reciprocate the traverse-bar C with a relatively short traverse; and by swinging the sector R on its pivot in the direction indicated by the arrow 2 the stud p is released so that it can be shifted to the upper end of the arm F, as shown in Fig. 8, to provide for the maximum throw or traverse of the traverse-bar. A spring S, see Fig. 9, preferably formed of wire bent in a helical coil at s, is secured at one end to the top of the arm 130

F by a screw s' . The lower end of the spring S is bent at right-angles and hooks through one of a series of holes r^3 , r^8 , arranged in an arc concentric to the axis of the 5 sector, so that the spring has a tendency to swing the sector in the direction opposite to that indicated by the arrow 2. The range of movement of the sector R is limited by the end of the spring striking the side of the 10 arm F and therefore its extent of movement can be regulated by adjusting the spring in the holes r^3 , r^8 , for a purpose as fully explained hereinafter. The sector R is normally restrained from movement under the 15 action of the spring S by a pawl T, the toe of which engages with the teeth r^2 , see Fig. 8. The pawl T is pivoted on a stud t screwed into the arm F and is formed with an offset tail-piece or arm t' , see also Fig. 3. The end 20 of the arm t' is rounded off on one side, as shown most clearly in Fig. 9, and this rounded edge is adapted to be engaged by the end of the link P as the stud p slides down in the slot f^8 . Such engagement will swing the 25 pawl T to release its end from the teeth r^2 and allow the sector to swing under the action of its spring S to engage the slot r' with the stud p . It is to be noted, however, that this engagement can take place only when 30 the hub f of the arm F is slid back from the clutch-block O into the position illustrated in Fig. 3. When the machine is operating and the hub f is engaged with the clutch-block O the link P lies against the face of 35 the arm F, as indicated by the dotted lines in Fig. 3, so that normally, the end of the link clears the offset arm t' . This provides that when the stud p is at the bottom of the slot f^8 , during the first stages of the winding, the end of the link will ride past and in 40 back of the arm T' without releasing the pawl T when the arm F oscillates.

The pawl T is normally maintained in engagement with the teeth r^2 on the sector R by 45 a spring U fastened to a standard V mounted on the flange f^7 of the arm F. The standard V is preferably constructed of sheet-metal and formed with a foot v secured to the flange f^7 by a screw v' . The spring U is 50 constructed of flat, spring-metal split into two branches u and u' , as shown in Fig. 7, and secured in place by a screw u^2 extending through its upper end. The end of the branch u engages the offset shoulder of the 55 arm t' of the pawl T, while the branch u' engages another element of the mechanism later described.

The sector R is swung in the direction indicated by the arrow 2, to release the stud p , 60 by the intermittent action of the pawl W actuated from the oscillating motion of the arm F, see Figs. 8 and 11. The pawl W is pivoted at the lower end of an elbow-shaped member 4, shown in detail in Fig. 6, which,

in turn, is pivotally mounted on the standard 65 V by means of the screw 5. The member 4 is preferably constructed of sheet-metal and the extremity of its lower arm 6 is bent outward to form a shoulder or abutment 7, see 70 Figs. 5 and 6, which serves as a stop to engage one side of the standard V. The lower end of the branch u' of the spring U engages the outer side of the abutment 7 to normally maintain it against the side of the standard V with the member 4 in the position illustrated in Fig. 8.

The pawl W is pivoted on a stud w screwed into the member 4 as shown more particularly in Fig. 5. The toe w' of the pawl is offset from its main portion and lies 80 directly under the teeth r^2 on the sector R with which it is adapted to engage. Bent forward from the main portion of the pawl is a finger w^2 which overlaps the edge of the member 4 and is adapted to engage 85 therewith to limit the downward movement of the toe w' . A wire spring 8 is bent around the stud w with its end extending up over the back of the finger w^2 and, preferably, a groove w^3 is formed on the edge 90 of the finger to retain the spring in place. The spring 8 is held from turning on the stud w by a nut w^4 set up against a washer w^5 which binds the spring against the member 4. Extending rearwardly from the 95 pawl W is an arm w^6 having its end bent inward at w^7 , as shown in Fig. 5. The spring 8 tends to normally maintain the pawl in the position illustrated in Fig. 8 with its toe w' just clear of the teeth r^2 of 100 the sector R. With the pawl W in this position the end of the arm w^6 is raised to adapt it to be engaged by the lower edge of the link P when the arm F is rocked into its rearward position as illustrated in Fig. 11. 105 This engagement takes place only when the stud p is at the bottom of the slot f^8 in the arm F, but during this time the arm w^6 will be engaged at each rearward oscillation of the arm F. The engagement of the link P 110 with the arm w^6 rocks the pawl W to carry its toe w' into engagement with the teeth r^2 and the movement of the pawl is then continued forward to swing the member 4 on its pivot so that the sector R is swung in 115 the direction indicated by the arrow 2 to shift it one tooth on the holding pawl T, as more fully explained hereinafter.

Referring to Fig. 8, the arm F has a transverse counterbore at f^9 with a smaller bore 120 f^{10} at its end, reaching into the slot f^8 . Mounted in the bore f^{10} is a plunger 9 formed with a head 10 which slides in the counterbore f^9 . A spring 11, retained in the counterbore by a screw 12, engages the 121 head 10 to force the end of the plunger into the slot f^8 , as shown more plainly in Fig. 9. Referring again to Fig. 8, the end of the

plunger 9 is rounded to adapt the stud p to ride over it when the latter is carried to the upper end of the slot f^3 , and the pressure of the spring 11 tends to hold the plunger in position to retain the stud at the end of the slot against the normal thrust on the link P.

Secured at one end to the top of the standard V is a flat, sheet-metal spring 13 held in place by the screw 14. The spring 13 is bent downward in a U-shaped loop with its free end 15 reaching up adjacent the end of the traverse-bar C'. The spring 13 is adapted to engage the end of the bar C' at each forward oscillation of the arm F and when the stud p is released from the sector R it acts to push the bar forward to carry the stud to the upper end of the slot f^3 as more fully explained hereinafter.

Referring to Fig. 3, it will be noted that the overhanging portion l^4 of the bridge-member L, which engages the projection f^2 on the rear end of the hub f , has a pin l^8 extending outward over the projection. The pin l^8 is adapted to engage with a depression or groove f^5 in the top of the projection f^2 when the arm F is rocked into its forward position, see Fig. 4. The engagement of the pin l^8 with the groove f^5 takes place only when the arm F is disconnected from the clutch-block O, as shown in Fig. 3. That is to say, during the operation of the machine the bridge-member L is in such position that its overhanging portion l^4 is raised free of the projection f^2 on the hub f , as shown by dotted lines in Fig. 3, and consequently the pin l^8 is out of range of the groove f^5 in the top of the projection. When the bridge-member L is rocked to stop the machine its overhanging portion l^4 is brought down into engagement with the beveled edge of the projection f^2 , as shown by full lines in Figs. 3 and 4, and previously described, and the pin l^8 is carried into position to engage the groove f^5 . The object of this engagement is to hold the arm F at the forward end of its stroke so that the traverse-controlling mechanism may be set in its initial position to start the winding of the bunch, as more fully described hereinafter. It is also to be noted that it is not necessary for the arm F to be in its forward position when the portion l^4 of the member L rocks downward in order to effect this engagement of the pin l^8 with the groove f^5 . Should the movement of the arm F be arrested in any position other than that at the forward end of its stroke the projection f^2 can be swung over under the pin l^8 by simply rocking the arm F forward. Such movement of the arm is effected manually by pulling the traverse-rod C outward through its bearing in the frame A. It will be observed from Fig. 4 that the forward edge of the projec-

tion f^2 is rounded off at f^6 to adapt the pin l^8 to ride up onto the top of the projection and the inherent spring tendency of the pin causes it to spring down into the groove f^5 when the latter comes into alignment with the pin.

The operation of the whole machine is as follows: Referring first to Figs. 1 and 2, we have here shown a wooden bobbin x of usual form applied to the winding-spindle B, but other forms of holders for the yarn, such as paper cop-tubes, for instance, might be employed with equal effect. Figs. 1 and 2 illustrate the machine at the beginning of the winding and we have shown the traverse rocker-arm F at the forward end of its throw. It is obvious, however, that the machine will not always stop with the arm F in this position, nor is it necessary, because, before starting the winding the operator must set the bunch-building mechanism and he is instructed to perform the following operations: The first step taken is to pull the traverse-bar C outward in the direction indicated by the arrow 3, see Fig. 1, and if the arm F is in any other position than at the forward end of its stroke it will be rocked forward until the pin l^8 engages the groove f^5 in the projection f^2 of the hub f . This engagement of the pin and groove locks the arm F in its forward position, as shown in Figs. 1 and 4. The operator now pushes the traverse-bar C backward in the opposite direction and, the arm F being held from movement, the stud p on the link P is forced down to the bottom of the slot f^3 .

During the time the machine is operating to wind with the full traverse of the thread-guide the sector R remains in the position illustrated in Fig. 8, being held against the action of the spring S by the pawl T. It will be noted that the upper edge of the slot r' of the sector R is rounded off and forms a point r^4 projecting from the forward edge of the upper part of the sector. With the sector R in the position illustrated in Fig. 8 the point or abutment r^4 projects part way across the slot f^3 of the arm F. Now, as the stud p is pushed down in the slot f^3 it will ride up over the rounded edge of the abutment r^4 and force the sector back into the position shown in Fig. 9. It must be noted, however, that this movement of the sector R under action of the stud p does not carry it back far enough for the pawl T to engage another tooth on its lower edge, but only releases the pawl from the tooth first engaged. This provides that as the stud p is pushed still farther down in the slot f^3 and the end of the link P comes into contact with the arm t' of the pawl T the latter will be free to be moved by the link to carry its toe out of range of the teeth r^2 . In other words, the pawl T is first released

from its binding engagement with the tooth r^2 by the slight rearward movement of the sector R so that it is free to be operated by the link P which engages its arm t' . The 5 pawl T will then be held free of the teeth by the link P while the stud p passes the abutment r^4 and the sector R will be swung back under action of the spring S to engage the slot r' with the stud. The sector R 10 swings back over the stud p until the end of the spring S strikes the arm F and the extent of this movement depends upon the location of the end of the spring S in the holes r^3 . This movement of the sector can 15 be adjusted by changing the spring to different holes, as before described, and in this way the extent of movement required to release the stud from the sector can be varied to regulate the number of reciprocations of 20 the thread-guide with the short traverse, as further explained hereinafter. In the drawings we have shown the spring S adjusted in the last hole, so as to provide for a maximum movement of the sector R before the stud p 25 is released, and consequently a relatively large number of reciprocations of the guide will take place with the short traverse and hence a comparatively long length of yarn will be wound into the bunch. The parts as 30 last described are now in the position illustrated in Fig. 10 and the bunch-building mechanism is set ready to wind the first layers of the bobbin with a short traverse. The thread-guide G is next adjusted in its rearward position on the traverse-bar C, as 35 shown in Fig. 2, and the yarn y is threaded through with its end secured to the bobbin x .

The operation of the machine is started by turning the handle M' which operates the 40 bridge-member L to release its lever l^3 from the clutch-member N, it being understood that the member L is withheld from action by suitable detents, not here shown. As the clutch-member N is released it is carried 45 into engagement with the gear e' , through the action of the spring n' , and the rotation of the gear imparts rotation to the winding-spindle B. Concurrently with the release of the clutch-member N, the projection 50 f^2 is also released from engagement with the member L and the hub f of the arm F slides into position to engage the clutch-block O, under the influence of the spring o^2 . As the slot o' rocks into alignment with the spline f' on the hub f the two 55 are engaged and in this manner the arm F is connected to the rocker-shaft D and is oscillated thereby. As the hub f slides into engagement with the clutch-block O the arm 60 t' moves laterally with it and rides off the end of the link P which comes up against the face of the arm F, assuming the position illustrated by dotted lines in Fig. 3, and previously described. This action releases the pawl T and allows its toe to en-

gage the teeth r^2 on the sector R, under influence of the spring U, as shown in Fig. 10. The stud p is now held at the bottom of the slot f^3 , and the rocking movement of the arm F is transmitted to the traverse-bar C 70 through the link P to impart a relatively short traverse to the thread-guide G. Each time the arm F moves back toward its rearward position, illustrated in Fig. 11, the lower edge of the link P strikes the end of 75 the arm w^6 of the pawl W and rocks the pawl to engage its toe with the teeth r^2 on the sector R. This engagement of the link P with the arm w^6 continues throughout a sufficient portion of the stroke of the arm F 80 to cause the member 4 to be swung back to move the sector R one tooth on the holding pawl T. Now, as the arm F swings back in the opposite direction the spring U acts to return the member 4 into position for the 85 pawl W to engage the next tooth r^2 , this backward movement of the member 4 being limited by the stop 7. In this way the sector R is shifted one tooth at each backward oscillation of the arm F until the stud p is 90 released from the slot r' . It will be understood that as the sector R is shifted each time the holding pawl T prevents it from returning, under action of its spring S, and it is to be noted that the movement of the 95 pawl W and the member 4 carries the sector slightly beyond the extent necessary for the pawl T to engage the next tooth. Referring to Fig. 9, this is provided in order that after the abutment r^4 has passed out of range of 100 the stud p , as here shown, and the stud is released, the sector can return to the position shown in Fig. 8 with the abutment slightly overlapping the slot r^3 . The purpose of this projection of the abutment r^4 across the slot 105 f^3 has been previously described in connection with the explanation of the preliminary setting of the mechanism; the object being to provide for the release of the toe of the holding pawl T from the teeth r^2 so that the pawl may be free to be moved by the end 110 of the link P.

After the sector R is moved to the position shown in Fig. 9 the stud p is free to slide up the slot f^3 and this is effected by the 115 pressure of the spring 13 which engages the end of the bar C' and pushes it in the direction indicated by the arrow 3, Fig. 1, during the forward movement of the arm F. Henceforth, the arm F will act through the 120 link P to impart the full length of traverse to the thread-guide. The stud p is maintained at the upper end of the slot f^3 against the normal thrust of the bar C' by the action of the spring-pressed plunger 9, as before described.

Referring to Fig. 2, it will be seen that 125 while the stud p is at the bottom of the slot f^3 the arm F will act to reciprocate the thread-guide with a comparatively short 130

traverse to form the bunch y' ; while with the stud p at the upper end of the slot f^s the yarn is laid with a traverse substantially twice as long as illustrated by the layer y^2 . The number of layers or traverses of the yarn in the bunch y' is determined by the number of oscillations required to move the sector R into position to release the stud p and this can be varied by adjusting the spring S . As here illustrated the spring S is shown in the last hole r^s and as the holes correspond in number to the teeth r^2 twelve strokes of the arm F must take place before the stud p is shifted. When the spring S is moved to the hole nearest the arm F only one oscillation of the arm F is required to release the stud p , but usually the mechanism is not set as close as this. Our new device provides for a wide range 20 of adjustment, however, and can be set to wind either a very short length of yarn in the bunch or a considerable length if required. In this way the yardage of the bunch can be controlled accurately and 25 positively for each bobbin. This is a most important feature and provides against waste which would result if the bunch-building mechanism were arranged to be controlled manually. The yardage required 30 in the bunch depends upon the width of cloth to be woven from the yarn on the bobbin and it is very necessary to have a sufficient length so that the shuttle will not become entirely exhausted in its last throw 35 across the loom before a new bobbin is supplied. For this reason it has been the custom to provide considerable more than enough yardage in the bunch to prevent "miss-picks" and where the human factor 40 is an element in determining the proper yardage it is inevitable that there will be considerable waste. With our new device the mechanism can be set by a competent overseer to provide the proper yardage in 45 the bunch, and all the bobbins will then be wound uniformly according to requirements. Furthermore, in our present embodiment 50 of the invention the bunch-building device can be applied to machines now in use with but slight alteration of their mechanism and such machines are rendered interchangeable 55 for other methods of winding.

It is obvious that our new device might be applied to machines of different design from that here shown and described, or adapted for other arrangements of winding mechanism. For instance, the controlling-device for regulating the extent of traverse with which the yarn is wound might be arranged to operate in connection with a traverse-mechanism for reciprocating the winding-spindle in respect to the guide instead of reciprocating the guide itself.

Various modifications might also be made in the form and structure of the parts of

our device without departing from the spirit or scope of the invention; therefore, without limiting ourselves to the exact arrangement shown and described, what we claim is:—

1. In a winding machine, the combination with the winding-spindle, of a traverse-bar adapted to be reciprocated in the direction of its axis with respect to the spindle, a thread-guide on said bar, means to feed said guide progressively along the bar during the reciprocation of the latter, means to reciprocate the bar with a minimum and maximum extent of traverse, controlling-devices co-operating with the reciprocating means to cause the bar to be reciprocated with the minimum extent of traverse during a predetermined number of reciprocations, and means for adjusting the controlling-devices to determine the number of reciprocations during which the bar is reciprocated with the minimum extent of traverse. 70

2. In a winding machine, the combination with the winding-spindle, of a traverse-bar, a thread-guide mounted on said bar, means to cause a relatively longitudinal reciprocation between the spindle and bar, means to feed the thread-guide progressively along the bar during the winding, controlling-means co-operating with the reciprocating-means to cause the thread-guide to lay the yarn with a relatively short extent of traverse during a predetermined number of reciprocations of the traverse-bar to build a "bunch" on the bobbin, and means to adjust the controlling-means to determine the number of reciprocations during which the yarn is laid with the short extent of traverse. 90

3. In a winding machine, the combination with the winding-spindle, of a traverse-bar adapted to be reciprocated in an axial direction with respect to said spindle, a thread-guide mounted on said bar, means to feed the guide progressively along the bar during its reciprocation, means to reciprocate the bar with different extents of traverse, controlling-devices co-operating with the reciprocating-means to cause the bar to be reciprocated with a relatively short traverse, means actuated by the reciprocating-means after a predetermined number of reciprocations to cause the bar to be reciprocated with a longer traverse, and means 110 adjustable to vary the number of reciprocations of the bar with the short traverse. 115

4. In a winding machine, the combination with the winding-spindle, of a traverse-bar adapted to be reciprocated with respect to the spindle, a thread-guide mounted on said bar, means to feed said guide progressively along the bar during its reciprocation, means to reciprocate the bar with different extents of traverse, controlling-devices co- 125 130

operating with said means to cause the bar to be reciprocated with a relatively short traverse, means actuated by the reciprocating-means at each reciprocation of the bar to operate the controlling-means after a predetermined number of reciprocations to cause the bar to be reciprocated with a longer traverse, and means adjustable to determine the number of reciprocations of the bar with the short traverse.

10 5. In a winding machine, the combination with the winding-spindle, of a traverse-bar adapted to be reciprocated with respect to the spindle, a thread-guide mounted on said bar, means to feed the guide progressively along the bar during its reciprocation, an oscillating arm for reciprocating the bar, means to cause the arm to reciprocate the bar with a relatively short traverse, means operated after a predetermined number of oscillations of the arm to cause the latter to reciprocate the bar with a longer traverse, and means adjustable to regulate the number of reciprocations of the bar before the 20 change in the traverse.

25 6. In a winding machine, the combination with the winding-spindle, of a traverse-bar adapted to be reciprocated with respect to the spindle, a thread-guide mounted on said bar, means to feed the guide progressively along the bar during its reciprocation, an oscillating arm for reciprocating the bar, means to cause the arm to reciprocate the bar with a relatively short traverse, devices 30 operating to release said means after a predetermined number of reciprocations of the bar, means to cause the bar to be reciprocated with a longer traverse after the release of the first named means, and means 35 adjustable to regulate the time of operation of the releasing-means.

40 7. In a winding machine, the combination with the winding-spindle and thread-guide, of an oscillating member having a constant stroke, means on said member connected to reciprocate the guide therefrom, devices to maintain said means at a point adjacent the axis of said member to cause the guide to be reciprocated with a relatively short traverse to build a "bunch" at the beginning of the bobbin, devices operating at the completion of the "bunch" to automatically shift said means on the member to cause the guide to be reciprocated with a relatively longer traverse to wind the main portion of the bobbin, and means adjustable to regulate the number of reciprocations of the guide with the short traverse to control the length of yarn wound into the 50 "bunch".

60 8. In a winding machine, the combination with the winding-spindle and thread-guide, of an oscillating arm for reciprocating the guide, means adapted to connect the 65 guide with the arm at different distances

from the axis about which the latter oscillates, means to retain the connecting-means at a point relatively near the axis of the arm during a predetermined number of reciprocations to wind a number of layers of 70 comparatively short traverse for forming a bunch on the bobbin, means to move the connecting-means away from the axis of the arm to cause the guide to wind the main portion of the bobbin with a longer traverse, 75 and means adjustable to regulate the time of action of the last named means to determine the length of yarn wound into the bunch.

9. In a winding machine, the combination with the winding-spindle and thread-guide, 80 of an oscillating arm for reciprocating the guide, means adapted to connect the guide at different points on the arm to vary the operative effect of the latter, means to maintain the connecting-means in position to 85 cause the arm to reciprocate the guide with a relatively short traverse, means operated by the oscillation of the arm to shift the connecting-means after a predetermined number of oscillations to cause the guide to be 90 reciprocated with a longer traverse, and means adjustable to vary the time of action of the shifting-means.

10. In a winding machine, the combination with a winding-spindle and thread-guide, 95 of an oscillating arm for reciprocating the guide, means connecting the guide with the arm and adapted to slide on the latter to vary the operative effect of its throw, a ratchet-member on the arm adapted to retain the connecting-means at a distance 100 away from the end of the arm, means to operate the ratchet-member at each oscillation of the arm to release the connecting-means after a predetermined number of oscillations, and means adjustable to regulate the number of operations of the ratchet-member required to effect the release of the 105 connecting-means.

11. In a winding machine, the combination with a winding-spindle and thread-guide, 110 of an oscillating arm for reciprocating the guide, means connecting the guide with the arm and adapted to slide on the latter to vary the operative effect of its throw, a member on said arm adapted to retain the connecting-means in position for the arm to impart a relatively short traverse to the guide, means operated at each oscillation of the arm to shift the retaining-member 115 to release the connecting-means after a predetermined number of oscillations, and means to adjust said retaining-member to regulate the number of operations required to effect the release of the connecting-means. 120

12. In a winding machine, the combination with a winding-spindle and thread-guide, 125 of an oscillating arm for reciprocating the guide, means connecting the guide with the arm and adapted to slide on the 130

- letter to vary the operative effect of its throw, a member on the arm adapted to retain the connecting-means in position for the arm to impart a relatively short traverse to the guide, means to move said member to a slight extent during each oscillation of the arm, and means to adjust said member to regulate the extent of movement required to release the connecting-means.
13. In a winding machine, the combination with a winding-spindle and thread-guide, of an oscillating arm for reciprocating the guide, means connecting the guide with the arm and adapted to slide on the latter to vary the operative effect of its throw, a member on said arm formed with ratchet teeth and adapted to retain the connecting-means at a distance away from the end of the arm, means to intermittently shift said member one tooth at each oscillation of the arm to release the connecting-means after a predetermined number of oscillations, and means to adjust the member to vary the extent of movement required for it to release the connecting-means.
14. In a winding machine, the combination with a winding-spindle and thread-guide, of an oscillating arm for reciprocating the guide, means connecting the guide with the arm and adapted to be shifted on the latter to vary the operative effect of its throw, a member adapted to retain the connecting-means at a point adjacent the axis of the arm, a spring tending to move said member to engage it with the connecting-means, and means to shift said member to cause it to release the connecting-means at a predetermined point in the winding.
15. In a winding machine, the combination with a winding-spindle and thread-guide, of an oscillating arm for reciprocating the guide, means connecting the guide with the arm and adapted to be shifted on the latter to vary the operative effect of its throw, a member adapted to retain the connecting-means at a distance away from the end of the arm, means to move said member to engage it with the connecting-means, means to normally hold the member against such movement, and means to release the holding-means.
16. In a winding machine, the combination with a winding-spindle and thread-guide, of an oscillating arm for reciprocating the guide, means connecting the guide with the arm and adapted to be shifted on the latter to vary the operative effect of its throw, a member adapted to retain the connecting-means at a distance away from the end of the arm, means to engage said member with the connecting-means, and means to hold the member against such engagement, said holding-means adapted to be released by the shifting of the connecting-means.
17. In a winding machine, the combination with a winding-spindle and thread-guide, of an oscillating arm, a connection between the guide and arm adapted to be shifted along the latter, a retaining-member pivoted on the arm and adapted to swing into engagement with the connection, a spring to swing the member, and a pawl operated during the oscillating movement of the arm to shift the member against the action of the spring to disengage it from the connection.
18. In a winding machine, the combination with a winding-spindle and thread-guide, of an oscillating arm, a connection between the guide and arm adapted to be shifted along the latter, a retaining-member pivoted on the arm and adapted to swing to engage it with the connection, a spring to swing the member into engagement with the connection, a pawl operated by the oscillation of the arm to intermittently shift the member against the action of the spring, and a second pawl adapted to hold the member in the position to which it is shifted by the first pawl.
19. In a winding machine, the combination with a winding-spindle and thread-guide, of an oscillating arm, a connection between the guide and arm adapted to be shifted along the latter, a retaining-member pivoted on the arm and adapted to be engaged with the connection to a greater or less extent, means adjustable on the retaining-member to regulate the extent of its engagement with the connection, and means operated during the oscillation of the arm to shift the retaining-member by degrees to release it from the connection.
20. In a winding machine, the combination with the winding-spindle and thread-guide, of an oscillating arm formed with a slot extending radially from its axis, a link connected with the guide and carrying a stud at its opposite end engaging the slot in the arm, a sector pivoted on the arm and formed with a slot adapted to engage the stud on the link, means to engage the sector with the stud, and means to shift the sector to release the stud at a predetermined point in the winding.
21. In a winding machine, the combination with the winding-spindle and thread-guide, of an oscillating arm, a link connected with the guide and having a stud at its opposite end slidable on the arm, a sector pivoted on the arm and formed with a slot adapted to engage the stud, means to adjust the extent of engagement of the sector with the stud, and means operating intermittently during the oscillation of the arm to shift the sector to release the stud after a predetermined number of oscillations.
22. In a winding machine, the combination with the winding-spindle and thread-guide, of an oscillating arm, a link connected

with the guide and carrying a stud at its opposite end slideable along the arm, a sector pivoted on the arm and formed with an arcuate slot adapted to slide over the 5 stud, said sector formed with ratchet teeth, a spring to swing the sector to engage its slot with the stud, a pawl pivoted on the arm and adapted to engage the teeth on the sector to hold it against the action of the 10 spring, and a second pawl adapted to be actuated through engagement with the link at each oscillation of the arm to shift the sector tooth-by-tooth on the holding pawl.

23. In a winding machine, the combination with the winding-spindle and thread-guide, of an oscillating arm, a link connected with the guide and carrying a stud at its opposite end slideable along the arm, a sector pivoted on the arm and having a slot adapted 15 to slide over the stud, a spring to swing the sector to engage its slot with the stud, a pawl to hold the sector against the action of the spring, a swinging-member, and a pawl pivoted on the swinging-member and adapted 20 to be moved therewith to shift the sector on the holding pawl.

24. In a winding machine, the combination with the winding-spindle and thread-guide, of an oscillating arm, a link connected 25 with the guide and having a stud slideable along the arm, a sector pivoted on the arm and formed with a slot adapted to slide over the stud, a spring to swing the sector to engage its slot with the stud, a pawl pivoted 30 on the arm and adapted to engage the sector to hold it against the action of the spring, a standard mounted on the arm, a swinging-member pivoted on the standard, a pawl pivoted 35 on the swinging-member and adapted to be engaged by the link to carry it into engagement with the sector, and a spring 40 to normally maintain said pawl out of engagement with the sector.

25. In a winding machine, the combination with the winding-spindle and thread-guide, of an oscillating arm, a link connected 45 with the guide and having a stud slideable along the arm, a sector pivoted on the arm and having a slot adapted to engage the 50 stud, said sector formed with ratchet teeth, a spring to swing the sector to engage its slot with the stud, and a pawl adapted to engage the teeth on the sector to hold the latter against the action of the spring, said 55 pawl having an arm adapted to be engaged by the end of the link when the stud is moved inward on the arm to release the pawl from the teeth on the sector.

26. In a winding machine, the combination with the winding-spindle and thread-guide, of an oscillating arm having a slot extending radially from its axis, a link connected with the guide and carrying a stud adapted to slide along the slot in the arm, a toothed sector pivoted on the arm and formed with a slot adapted to engage with the stud, said slot terminating in an abutment extending across the slot in the arm and adapted to be engaged by the stud before the latter enters the slot in the sector, 65 and a pawl engaging the teeth on the sector and adapted to be released therefrom when the sector is moved through engagement of its abutment by the stud.

27. In a winding machine, the combination with the winding-spindle and thread-guide, of an oscillating arm, a link connected with the guide and carrying a stud adapted to slide along the arm, a swinging sector pivoted on the arm and formed with a slot 70 adapted to slide over the stud, said sector having a series of holes, and a wire spring secured to the arm with its end adapted to swing the latter, the end of the spring being 75 adapted to engage the side of the arm to limit the swinging movement of the sector.

28. In a winding machine, the combination with the winding-spindle and thread-guide, of a traverse-bar for reciprocating 80 the guide, an oscillating arm, a link connected to the traverse-bar with its opposite end adapted to slide along the arm, means to retain the link at a point away from the end of the arm, devices to release said retaining-means, and a spring adapted to engage the end of the traverse-bar during the oscillation of the arm to slide the bar to carry the link to the end of the arm.

29. In a winding machine, the combination with the winding-spindle and thread-guide, of an oscillating arm formed with a slot extending radially from its axis, a link connected with the guide and carrying a stud slideable along the slot in the arm, a 100 plunger slideable in the arm to project its end into the slot, and a spring to slide the plunger.

In testimony whereof we affix our signatures in presence of two witnesses.
